DESCRIPTION

FIG. 1 is a rear perspective view of a shoe showing my new design;
 FIG. 2 is a side view thereof;

FIG. 3 is a rear view thereof;

FIG. 4 is an opposite side view thereof; and,

FIG. 5 is an opposite side rear perspective view thereof.
 The broken lines immediately adjacent to the shaded areas define the bounds of the claimed design and form no part thereof. The broken lines depicting the remainder of the shoe form no part of the claimed design.

1 Claim, 5 Drawing Sheets
